UNITED STATES PATENT OFFICE.

ROBERT BLYTHE GOODWIN, OF MEMPHIS, TENNESSEE.

MUCILAGE-CONTAINER.

1,273,478.

Specification of Letters Patent. Patented July 23, 1918.

Application filed February 6, 1918. Serial No. 215,718.

To all whom it may concern:

Be it known that I, ROBERT BLYTHE GOODWIN, a citizen of the United States, residing at Memphis, Shelby county, and State of Tennessee, have invented and discovered certain new and useful Improvements in Mucilage-Containers, of which the following is a specification.

This invention relates to containers for mucilage or other liquid adhesives and consists of a reservoir for the mucilage having formed integrally therewith the means for delivering and spreading its contents, and a support for holding the reservoir when not in use.

One object is to provide a container which is at all times ready for use and which is designed in such a way that only a very small surface of the adhesive contained therein is exposed to the drying action of the atmosphere. Another object is to provide a mucilage spreader which will not retain any surplus mucilage around the edges of the spreader portion.

With these and other objects in view, the invention consists of a combination and arrangement of parts clearly described in the specification and particularly pointed out in the appended claim, reference being had to the accompanying drawing which shows a vertical longitudinal section through both the container and the support.

In the drawings, 5 represents the support which is composed of a cylindrical portion 6 having a flared base 7 which prevents accidental upsetting of the device. The portion 6 is hollowed out as at 8 to form a cup for the reception of an adhesive reservoir 9 preferably constructed of rubber, and having formed integrally therewith a tapering extension 10 which may be of either flexible or hard rubber and of such length that the open end 11 will not come in contact with the floor of the hollow portion 8 of the base.

As a means of preventing the adhesive

from becoming dry while in the reservoir, the opening 11 is made small so that only a very small portion of the adhesive is exposed to the drying action of the air. Therefore, should the device be left standing for any length of time a small film will form over the mouth of the opening, which besides sealing the opening, is so small that slight pressure on the bulb will displace the film allowing the adhesive to be forced out.

In the operation of the device, it is only necessary to slightly compress the bulb 9 which will cause the adhesive therein to be emitted from the opening 11 and applied directly to the articles to be secured. The adhesive may, if necessary, be spread over the surface by means of the end of the tapering extension. With the device as constructed, there is no brush necessary and therefore no waste of material due to the adhesive being scraped off and left sticking to the cup.

Having thus described my said invention, what I claim as new and desire to secure by Letters Patent is:

A mucilage dispenser comprising a spherical and collapsible reservoir having an integral tapering portion tapering to provide an aperture of comparatively small cross section whereby to provide a substantially air tight seal to the contents of the reservoir body, and to serve for discharging the mucilage, said tapering extention being flexible and adapted for spreading the mucilage on the surface to be sealed, and a support for the reservoir when not in use, substantially as set forth.

In witness whereof, I have hereunto set my hand and seal at Memphis, Tennessee this 22 day of January, A. D., nineteen hundred and eighteen.

ROBERT BLYTHE GOODWIN. [L. S.]
